UNITED STATES PATENT OFFICE.

HENRY VOIGHT, OF CINCINNATI, OHIO.

DESIGN FOR AN UPHOLSTERING-APPLIANCE CAP.

SPECIFICATION forming part of Design No. 31,243, dated July 18, 1899.

Application filed June 26, 1899. Serial No. 721,966. Term of patent 3½ years.

To all whom it may concern:

Be it known that I, HENRY VOIGHT, a citizen of the United States, residing at Cincinnati, in the county of Hamilton and State of Ohio, have invented and produced a new and original Design for an Upholstering-Appliance Cap; and I do hereby declare the following to be a full, clear, and exact description of the same, reference being had to the accompanying drawings, which form a part of this specification.

My invention comprises a design for a cap to be used with upholstering appliances of the kind disclosed in Letters Patent No. 624,134, issued to me May 2, 1899, the nature of said design being clearly shown in the accompanying drawings, in which—

Figure 1 is a side elevation of said cap. Fig. 2 is an axial section of the same, and Fig. 3 is a plan of the lower end of the cap. ²⁰

The cap has a tapering handle A and a hollow cylindrical body B, the outer surface of which body is provided with a series of longitudinal ribs b.

I claim as my invention—

The design for an upholstering-appliance cap, as herein shown and described.

In testimony whereof I affix my signature in presence of two witnesses.

HENRY VOIGHT.
